Patented Feb. 25, 1896.

UNITED STATES PATENT OFFICE.

WILLIAM W. WALLACE, OF WILLOUGHBY, OHIO, ASSIGNOR TO J. W. PENFIELD & SON, OF SAME PLACE.

BRICK-RE-PRESSING MACHINE.

SPECIFICATION forming part of Letters Patent No. 555,349, dated February 25, 1896.

Application filed October 17, 1895. Serial No. 566,025. (No model.)

To all whom it may concern:

Be it known that I, WILLIAM W. WALLACE, of Willoughby, in the county of Lake and State of Ohio, have invented certain new and useful Improvements in Brick-Re-Pressing Machines; and I do hereby declare the following to be a full, clear, and exact description of the invention, such as will enable others skilled in the art to which it pertains to make and use the same.

My invention relates to improvements in brick-re-pressing machines; and it consists in certain features of construction and combinations of parts, hereinafter described and pointed out in the claims.

In the accompanying drawings, Figure 1 is a front side elevation of a machine embodying my invention. Fig. 2 is a right-hand side elevation of the machine and has portions broken away to reduce the size of the drawing. Fig. 3 is a right-hand side elevation in vertical section and has portions broken away to reduce the size of the drawing to more clearly show the construction. Fig. 4 is a top plan in section on line 4-4, Fig. 1. Fig. 5, on sheet containing Fig. 2, is an elevation, mostly in vertical section, on line 5-5, Fig. 2. Fig. 6, on sheet containing Fig. 1, is an elevation in vertical section showing, among other things, one of the molds of the machine, the vertically-movable bottom of said mold, the plunger for compressing the brick within the mold from above, and the paneling device.

My improved machine comprises any suitable number of molds or dies A, wherein the bricks are re-pressed. The machine illustrated has two molds A arranged in the same horizontal plane and a suitable distance apart, and said molds are suitably supported between two upright standards B B. (See Figs. 1, 3 and 4.) Each mold has a vertically-movable bottom a for compressing the brick introduced into the mold from below and for elevating the brick, after the re-pressing operation, flush with the upper surface of the off-bearing portion of a belt or apron C that leads over any suitable number of pulleys or rollers C and is actuated in any approved manner.

The machine forward of the molds is provided with a horizontally-arranged table D,

whose upper surface is arranged flush with the upper edges of the molds and flush with the upper surface of the off-bearing portion of the aforesaid belt or apron.

A suitably-actuated longitudinally-reciprocating frame E is arranged upon table D. Frame E at its forward end is provided with a depending slide or guide e that engages and is adapted to move endwise of a slot or slide-way d formed within and longitudinally of table D. (See Figs. 3 and 4.) Frame E is suitably constructed to form followers E' adapted to push the brick that are deposited upon table D from a rearwardly-declining plate F, supported a suitable distance above the forward portion of said table, rearwardly onto the vertically-movable bottoms of the molds. Frame E is reciprocated forwardly preparatory to the reception of the bricks to be re-pressed in under plate F, whereupon the bricks are placed upon said plate and those that require re-pressing are pushed forwardly in front of members E' of frame E, whereupon said frame is reciprocated in the opposite direction the distance required to convey the bricks to be re-pressed to the movable bottoms of the molds.

The mechanism for actuating frame E is preferably as follows: Said frame at its rear end and central portion is operatively connected by means of a link E² with the outer or lower end of an arm or lever E³, that depends from and is operatively mounted upon a horizontally-arranged oscillating shaft E⁴, suitably supported from standards B. Shaft E⁴ at one end (see Figs. 1 and 2) is provided with another depending arm or lever, e⁵, that, at its lower end, is also operatively connected by means of a link E⁵ (see Fig. 2) with the upper end of a tilting lever E⁶, that is fulcrumed at its lower end, as at E⁷, to any stationary object—such, for instance, as the supporting-frame of the machine—and at a suitable distance from its fulcrum is provided with a roller E⁸, that engages a cam groove or way g of a cam-wheel G operatively mounted upon a suitably-driven shaft G', arranged horizontally and transversely of the machine. It will, therefore, be observed that reciprocating frame E is operated by cam-actuated lever 100

mechanism, and any lost motion in said mechanism is taken up by means of a weighted arm E⁹, operatively connected with shaft E⁴.

The mechanism for moving the movable mold-bottoms upwardly during their up-and down movement within the molds is preferably as follows: Each of said bottoms (see Figs. 1 and 3) is provided with a depending stem a'. Stems a' rest upon the heads of set-screws a², that are screwed into and form a part of the outer ends of a heavy arm a³ of an oscillating shaft a⁴, that is arranged horizontally of and suitably supported from the supporting-frame of the machine at any suitable point between the molds and shaft G', and shaft a⁴ is also provided with a depending rock-arm a⁵, that, at its lower end, bears a roller a⁶, engaging the peripheral surface of a cam G², operatively mounted upon shaft G'. The arrangement of parts is such that the movable mold-bottoms are elevated through the instrumentality of cam G² and the engaging-lever mechanism, and said bottoms are lowered by their gravity in conjunction with the gravity of arm a³.

H designates the plungers for compressing the brick from above. The machine is provided with as many plungers H as it has molds, and the machine illustrated has, therefore, two plungers H, that are arranged a suitable distance apart above and adapted to enter the different molds, respectively, of the machine. Each plunger H (see Fig. 3) is provided with two pressure-surfaces h' and h², and pressure-surface h' is arranged outside of and surrounds pressure-surface h². Pressure-surface h' is formed upon the under side of a quadrangular metallic block H', that extends round metallic block H², upon whose under side pressure-surface h² is formed. Block H' is shown removably secured by screws I to an external flange k' formed upon the lower end of the restricted or reduced portion k of an upright cylindrical case or receptacle K.

Block H² is capable of moving downwardly below the outer pressure-surface h', as will hereinafter appear. Block H², at its central portion, is provided with an upright stem H³ that engages the restricted portion k of case K internally and is provided centrally with a vertical screw-threaded hole h³, that is engaged by the lower correspondingly-threaded end of an upright stud L, that extends upwardly through a hole m provided centrally in the upper end of a cap M that fits over case K and has a limited movement up and down upon said case K. A pin N, that extends through a lateral hole M' in cap M and engages an upright groove or recess K' in case K, prevents circumferential displacement of case K within cap M. A strong stiff spiral spring O is seated upon the bottom K² of case K, and the upper coil of said spring is engaged by any suitable number of set-screws O', that engage correspondingly - screw-threaded holes m' provided in the upper end of cap M, and by means of which the tension

of the springs can be regulated. Stud L extends a suitable distance above cap M, and the upper protruding end of said stud is screw-threaded externally and engaged by a correspondingly-threaded nut L, and a spiral spring L² is confined upon the stud between the inner surface of the upper end of cap M and the upper end of the stem H³ of block H². Caps M of the different plungers are integral or rigid with a cross-bar or cross-beam M² that, adjacent to each standard B, is provided with a slide M³, suitably engaging and adapted to reciprocate up and down the respective standard that forms a slideway for the slide. Two links M⁴ (see Fig. 1) operatively connect opposite ends, respectively, of cross-bar or transversely-arranged member M² with different arms P' of an oscillating shaft P that is suitably supported from and transversely of the stationary framework of the machine and is arranged horizontally a suitable distance below the molds of the machine. Shaft P, at its central portion, is provided with a pair of depending rock-arms P² to and between the free ends whereof one end of a link P³ is suitably pivoted, which link P³, at its opposite end, is operatively connected with a crank G³ formed upon shaft G'. 95

Q designates the driving-shaft that is suitably supported and arranged horizontally at any suitable point between shafts P and G', and is suitably intergeared, as at Q', with said shaft G', and at any suitable point— such, for instance, as at one side of the machine—is provided with a driving-pulley Q², to which power is applied in any approved manner. The reciprocation of plungers H is, therefore, effected by shaft and lever mechanism operatively connected with shaft G', and the mechanism employed for preventing lost motion in the upward movement of the plungers is preferably as follows: Each slide M³ of member M is operatively connected by means of a downwardly-extending link m³ (see Figs. 1 and 2) with the forward end of a vertically-tilting lever m⁴, that is pivoted at m⁵ to the supporting-frame, and at its rear end is operatively connected with two depending rods m⁶, (see also Fig. 5,) arranged a suitable distance apart and extending through two horizontally-arranged plates m⁷ located a suitable distance apart. The lower plate, m⁷, rests upon nuts m⁸, mounted upon the lower screw-threaded ends of rods m⁶. A spiral spring m⁹ is confined between the two members m⁶, and an upright bolt m¹⁰, whose head engages the upper surface of the upper plate, m⁶, extends downwardly through both plates m⁶, and, a suitable distance below the lower plate, is suitably secured to the stationary framework of the machine. Whenever, therefore, the downward movement of the plungers takes place, tilting lever m⁴ is actuated in the direction required to elevate the lower plate, m⁷, and thereby compress the engaging-spring, the recoil whereof not only facilitates the upward movement of said 115 120 125 130 135

plungers, but prevents any lost motion in the upstroke of the plungers.

Operative connection between shaft G' and the off-bearing belt (see Figs. 2 and 3) is 5 preferably established by a sprocket-wheel G^4 , operatively mounted upon said shaft G' and operatively connected by means of a sprocket-chain G^5 with a sprocket-wheel C^2 operatively connected with one of the rollers 10 or pulleys engaged by the off-bearing belt.

My invention not only involves a machine that is exceedingly simple and durable in construction, but the two pressure-surfaces h' and h^2 with which each plunger H is 15 provided and their manner of operation is of vast importance, because by said construction, as will presently appear, the molds of the machine need not be provided with relief-holes, and the bricks operated upon by 20 the machine are re-pressed uniformly and to a uniform size. This uniformity in the compression of the brick and in the size of the re-pressed bricks is obtained by the peculiar construction of plunger hereinbefore described. 25 The outer pressure-surface, h' , of the plunger will during the descent of the plunger first engage the brick to be re-pressed and will compress the latter, and member k' of the plunger at one or more points is provided 30 with a stop k^2 (see Fig. 1) for limiting the descent of the outer pressure-surface of the plunger. Stops k^2 do not, however, interfere with the further descent of the inner pressure-surface of the plunger, and consequently, 35 during the further descent or downward movement of the plunger-bearing member M^2 and the caps M rigid with said member, the inner pressure-surface, h^2 , will be yieldingly advanced against the action of spring O and 40 impress a panel R' (see Fig. 6) within the brick R being re-pressed. Hence it will readily be observed that if the brick being re-pressed has more material in it than required the panel formed in the brick will simply not be 45 as deep as would be the case if the brick were composed of less material, and also if the bricks to be re-pressed simultaneously in the different molds of the machine do not have the same size or have not the same density the 50 operation of the machine or the work performed by the machine will not be affected, but the upper surfaces of all the bricks simultaneously re-pressed would be perfectly horizontal, and any difference between said bricks 55 would simply consist in the depth of their panels.

Springs O and L^2 cause the pressure-surfaces of the plungers to yieldingly perform their function. In the normal position of 60 parts the inner pressure-surface, h^2 , of the plunger is flush with the outer pressure-surface, h' , of the plunger, as shown in Fig. 3, and spring L^2 acts in the direction to retain the inner pressure-surface in said position.

65 The operating portions of the machine are, of course, so arranged and timed that the movable bottoms of the molds shall be ele-

vated flush with the upper surface of table D preparatory to the delivery of the bricks to be re-pressed from said table by frame E , 70 whereupon said bottoms are permitted to descend, and thereby lower the bricks into the molds, whereupon plungers H enter the molds from above and compress the contents of the molds, as hereinbefore described, and the 75 shape of the cam instrumental in the actuation of the mold-bottoms is preferably such as to elevate said bottoms more or less during the compression of the bricks by plungers H , so that the bricks during the re-pressing 80 operation are operated upon both from above and below, and after the re-pressing operation the receding or upstroke of plungers H is quickly effected and the movable mold-bottoms are again moved upwardly to elevate 85 the re-pressed bricks flush with the upper surface of the off-bearing portion of belt or apron C , whereupon frame E is again actuated to convey other bricks requiring re-pressing to the mold-bottoms and said incoming bricks 90 push the re-pressed bricks upon the mold-bottoms from the latter onto the off-bearing apron or belt.

The stationary framework or supporting-frame of the machine is preferably constructed to form a practically-closed case below the molds and adjacent portions of table D and belt or apron C , and said case is provided with any suitable number of doors S , that afford 95 access to the interior of the case. 100

What I claim is—

1. In a brick-re-pressing machine, a plunger for compressing the brick from above and comprising two pressure-blocks H' and H^2 , arranged the latter within the former, with 105 the inner pressure-block movable below the outer pressure-block, means for limiting the descent of the outer block, upright case or receptacle rigid with the outer block, a suitably-actuated vertically-reciprocating cap 110 embracing said case or receptacle, an upright stud or member rigid with the inner pressure-block and operatively connected with said cap, and a spiral spring confined upon said stud or connecting member between the inner pressure-block and upper end of the cap, substantially as shown, for the purpose specified. 115

2. In a brick-re-pressing machine, a plunger for compressing the brick from above and comprising two pressure-blocks H' and H^2 arranged the one H^2 within the other, and the inner pressure-block being movable below the outer pressure-block, suitable means for 120 limiting the descent of the outer pressure-block, an upright receptacle or case K rigid with the outer pressure-block, a suitably-actuated vertically-reciprocating cap M embracing said case or receptacle, spring O confined within the case or receptacle between 125 the lower end of the latter and the upper end of the cap, a stud or member L rigid with the inner pressure-block and operatively connected with the cap, and the spiral spring L^2 130

confined upon said stud or connecting member between the inner pressure-block and upper end of the cap, substantially as shown, for the purpose specified.

5 3. In a brick-re-pressing machine, the combination with two molds arranged a suitable distance apart and a plunger for each of said molds for compressing the brick introduced within the respective mold from above, each 10 plunger comprising two pressure-blocks H' and H^2 , the one H^2 whereof is arranged within the other H' , the pressure-surfaces of the two blocks being normally flush or approximately flush with each other, and the inner pressure-block being movable below the outer pressure-block, a stop for limiting the downward movement of the outer pressure-block, an upright case or receptacle K rigid with said outer

block, a cap M embracing said case or receptacle, an upright stud or member L^2 rigid 20 with the inner pressure-block and operatively connected with the cap, a spring confined upon said stud or connecting member between the inner pressure-block and upper end of the cap, and the caps of both plungers 25 being rigid with each other and forming a part of a suitably-actuated vertically-reciprocating cross-bar or beam, substantially as shown, for the purpose specified.

In testimony whereof I sign this specification, in the presence of two witnesses, this 2d day of August, 1895.

WILLIAM W. WALLACE.
